C. I. HALL

PROTECTIVE RELAY

Filed August 8, 1924

Inventor:
Chester I. Hall,
by *Alexander S. Lane*
His Attorney

UNITED STATES PATENT OFFICE.

CHESTER I. HALL, OF FORT WAYNE, INDIANA, ASSIGNOR TO GENERAL ELECTRIC COMPANY, A CORPORATION OF NEW YORK.

PROTECTIVE RELAY.

Application filed August 8, 1924. Serial No. 730,985.

To all whom it may concern:

Be it known that I, CHESTER I. HALL, a citizen of the United States, residing at Fort Wayne, in the county of Allen, State of Indiana, have invented certain new and useful Improvements in Protective Relays, of which the following is a specification.

The present invention relates to protective relays for electric translating devices, particularly temperature relays which are arranged to duplicate the heating characteristics of the electric translating devices to be protected, and the object of the invention is to provide a simple and effective device of the above character embodying means for changing the current carrying capacity thereof without changing its thermal characteristics.

One form of temperature relay to which my present invention is applicable is described fully and claimed broadly in my prior Patent No. 1,501,017 of July 8, 1924. Such a relay is designed to protect an electric translating device, as for example a motor, a transformer or the like, from injurious heating under overload or other abnormal temperature conditions by duplicating the thermal characteristics of the device in the relay itself. As more fully set forth in my above patent, a preferred form of the relay consists of a thermal responsive element which carries the load current of the electric device to be protected and also is in heat conducting relation with a heat storage mass which is provided with an electrical heating coil connected in series circuit with the thermal responsive element. The thermal responsive element is proportioned so as to duplicate the thermal characteristics of the winding of the translating device to be protected and the heat storage mass is proportioned so as to duplicate the thermal characteristics of the frame of the translating device.

The resulting time load heating characteristic of the relay is such as to duplicate that of the device being protected under all operating conditions.

It is often desirable to vary the current carrying capacity of a temperature relay of the above type to enable the relay to afford protection to an electrical translating device having a similar thermal characteristic but of greater current rating than that of the device which the relay was initially de-

signed to protect. Due to the predetermined coordination between the heating characteristics of the thermal responsive element and the heat storage mass, the calibration of the relay without materially changing the thermal characteristics thereof presents difficulties.

The usual method of varying the capacity of an electrical device by shunting the terminals thereof is unsatisfactory when applied to a relay of the above type, since the several current carrying parts of the relay are arranged to be heated to an operating temperature at different rates under varying conditions of overload. A shunt around the entire relay is objectionable since the distribution of the current between the shunt and the relay will vary under different conditions of overload and hence the relay will fail to duplicate accurately the heating characteristics of the machine to be protected. Furthermore, to increase the rating of the relay by shunting the terminals thereof would involve an increased wattage loss which is proportional to the increase in capacity and this is undesirable. Also the liability of mechanical derangement or misadjustment of such a shunt in service is a very serious objection.

However, by means of my invention the current carrying capacity of the relay is increased without changing the amount of current carried by the thermal responsive element or the wattage loss in the relay and thus the thermal characteristics of the relay remain unchanged.

Briefly, the increase in current carrying capacity of the relay is effected according to my invention by providing a shunt which is arranged to by-pass the increased current only from the thermal responsive element and conduct the heat generated thereby to the heat storage mass and at the same time varying the heating coil for the storage mass so that the heat generated therein with the increased current combined with that generated in the shunt is substantially the same as was supplied by the heating coil alone with normal current.

For a better understanding of my invention reference is had to the following description in connection with the accompanying drawing in which the single figure is a perspective view of a temperature relay embodying the invention.

Referring to the drawing, the temperature relay illustrated comprises a thermal responsive element 10 of the bi-metallic type, a heat storage mass 11 and an electrical heater 12. The heat storage mass 11 is divided into two parts which preferably are separated by an insulating partition of asbestos or the like and the thermal responsive element 10 is mounted upon suitable shoulders or bosses formed upon each portion of the thermal storage mass 11 so as to be in both electrical and heat conducting relation therewith. The free end of the element 10 is arranged to move into contacting engagement with the stationary contact 13 when the element 10 is heated to a predetermined temperature. It will be seen that the heating coil 12 is connected at one end to the relay terminal 14 and at the other end to the left hand portion of the heat storage mass 11.

In order to increase the current carrying capacity of the relay according to my invention, a shunt 15 for diverting the increased current from the thermal responsive element 10 is formed of a strip of suitable resistance material such as "advance" ribbon, which may be slotted as shown to permit one end thereof to be secured in intimate heat conducting relation with each portion of the storage mass 11 and at the same time furnish a path of suitable ohmic resistance in shunt with the thermal element 10. If the capacity of the relay is increased for example three times the resistance of the shunt would be one half that of the thermal element.

It will be observed that with this arrangement the heating effect of the current through shunt 15 is transmitted to the heat storage mass 11 rather than the thermal responsive element 10. This permits the heating coil 12 to be redesigned with a lower resistance such that with the increased current, the watt loss therein plus the watt

loss in the shunt 15 is the same as the watt loss of the heater alone in the original relay.

Since the physical proportions of the thermal element 10 and the heat storage mass 11 remain unchanged and also the watt loss applied to heating these respective elements with the increased capacity is the same as with the normal capacity it will be evident that the time load heating characteristics of the relay remains unchanged.

What I claim as new and desire to secure by Letters Patent of the United States is:

1. The combination with a temperature relay having a heat storage mass and a current carrying thermal element in heat conducting relation with said mass, of a shunt arranged to by-pass current from said element and conduct the heat generated thereby to said storage mass.

2. The combination with a temperature relay having a divided storage mass of metal and a current carrying thermal element in electrical and thermal connection with each portion of said storage mass, of a shunt for said element in heat conducting contact with each portion of said storage mass.

3. In a temperature relay, the combination of a heat storage mass, an electrical heater therefor, a thermal responsive element connected in circuit with said heater and in heat conducting relation with said storage mass, and a shunt for said element in heat conducting contact with said mass.

4. In a temperature relay, the combination of a divided storage mass of metal, a bi-metallic thermal element electrically and thermally connected to each portion of said mass, and means for heating said mass comprising a resistor in series connection with said element and a resistor in shunt connection with said element.

In witness whereof, I have hereunto set my hand this 4th day of August, 1924.

CHESTER I. HALL.
